to Metal Air Seals Company, a partnership
composed of C. Eugene Tovell and Walter J.
Levy

Application October 13, 1936, Serial No. 105,417

10 Claims. (Cl. 20—1.13)

This invention relates to storage racks and has particular reference to structures of this kind wherein alcoholic beverages, such as whiskey, gin, etc. are stored for long periods and/or to effect proper aging.

Among the objects of this invention is to provide a storehouse, with suitable rack construction, for inflammable liquids while undergoing storage and/or aging, said rack being provided 10 with means for reducing fire hazards and for effectively checking the spread of fire from one part of the structure to the other.

More specifically, it is an object of this invention to provide effective sealing means whereby 15 sections or parts of the rack are properly and effectively sealed from adjacent sections or parts of the rack so that a fire within one section will not spread to adjacent sections.

A further object of this invention is to provide, at properly spaced locations, metallic covering material over the gaps, cracks and other voids between adjacent structural members of the rack, said metallic covering material being disposed to provide sealed compartments wherein 25 each compartment comprises one or more floor levels or stories of the rack.

A still further object of this invention is to provide sprinkling means for each of the compartments heretofore described.

Other, further and more specific objects of this invention will become readily apparent to persons skilled in the art from a consideration of the following description when taken in conjunction with the accompanying drawings wherein:

Fig. 1 is a cross-section, substantially parallel to the end of a storage house, showing several stories in the upper portion of the building and illustrating the use of my invention in a wooden rack structure wherein the barrel supports are spaced to support the barrels at the chimes.

Fig. 2 is a fragmental cross-section along line 2—2 of Fig. 1.

Fig. 3 is a fragmental vertical section along lines 3—3 of Figs. 1 and 2.

Fig. 4 is a view similar to Fig. 3, showing the application of my invention to a wooden rack structure wherein the barrel supports are spaced to support the barrels between the chimes.

Fig. 5 is an enlarged detail fragmental view 50 showing the use of the sheet metal sealing means in the construction illustrated in Figs. 1, 2 and 3.

Fig. 6 is a view similar to Fig. 5 and showing the use of the sheet metal sealing means in the modified construction illustrated in Fig. 4.

Fig. 7 is a view similar to Fig. 3 and illustrating

the use of my invention in a metal rack structure wherein the barrel supports are spaced to support the barrels at the chimes.

Fig. 8 is an enlarged detail fragmental view 5 showing the use of the sheet metal sealing means in the construction illustrated in Fig. 7.

Fig. 9 is a detail fragmental view, more enlarged than Fig. 8, showing the manner of securing the sheet metal sealing means to the metal rack structure.

Fig. 10 is a view similar to Fig. 7, showing the application of my invention to a metal rack structure wherein the barrel supports are spaced to support the barrels between the chimes.

Fig. 11 is an enlarged fragmental view along line 11—11 of Fig. 10, showing the manner of securing the sheet metal sealing means to the metal rack structure.

Fig. 12 is an enlarged cross-section through the hallway at a floor level where sheet metal sealing means are used in the rack, and showing sheet metal sealing means applied to the floor.

Fig. 13 is a horizontal section through an elevator shaft in a storage house containing racks provided with my sheet metal sealing means and 25 showing the fire-excluding doors of the shaft in the vertical or open position.

Fig. 14 is a view similar to Fig. 13, but showing the fire-excluding doors of the shaft in the horizontal or closed position.

Fig. 15 is a fragmental view along line 15—15 of Fig. 13.

Referring to Figs. 1, 2, 3 and 5, the storage house is provided with a wooden rack structure 1 containing the hallways 2 which have the walks 3 at 35 each floor. From each side of each of these walks 3 extend the barrel supports 4 fastened upon the sills 6 resting upon the upright members 8. These upright members 8 also serve to support the barrel supports 4. The barrel supports 4, sills 6 and 40 upright members 8 form the spaces or cells 10 wherein the whiskey or other liquids are stored for aging and/or keeping. To utilize to full advantage the space in these cells 10, additional barrel supports 12 are provided in each cell. In 45 the illustration shown on the drawings, the barrels are supported at three elevations in each cell.

In order to afford proper facility for inspection of the cells 10 when filled with barrels, there are 50 provided the narrow passageways 14 with the treads or "cat-walks" 16. The cat-walks are at each floor and rest upon the sills 6. These passageways 14 may be provided between each pair of adjacent cells 10 or, as shown in Figs. 2 55

and 3, passageways provided alternately between pairs of cells can be employed.

An essential feature of this invention is the provision at one or more floors of the rack structure of the sheet metal seals 18 which are attached to the sills 6 and barrel supports 4. In the passageways 14, the sheet metal seals are preferably positioned below the treads or cat-walks 16. These sheet metal members 18 serve to separate and seal the space in the rack above such floor level from the space in the rack below such floor level so that, in case of fire, the flames in the space in the rack below such floor level will not travel to the space in the rack above such floor level.

These metal seals may be provided at each floor level, if desired, but, in general, I have found it sufficient to have these metal seals 18 at alternate floor levels, for example, at the third floor, 20 fifth floor, seventh floor, ninth floor, etc.

On the underside of the metal seals 18, preferably below the cat-walks 16, are attached sprinklers 20, conveniently distributed to supply fire-extinguishing fluid in conformity with the requirements of the Fire Underwriter's regulations. Water or other suitable fire-extinguishing fluid is supplied to these sprinklers through the risers or vertical manifolds 22 and the horizontal pipes 24. The sprinklers are provided with the customary material of low melting point, which fuses at a definite low temperature and releases the fire-extinguishing fluid.

The openings between adjacent barrel supports 4 in adjacent cells 10 are also sealed with sheet metal strips 26.

I also prefer to cover the underside of the walks 3 of the hallways 2 with sheet metal 28 in order to assure thorough sealing of such floor.

In the rack construction shown in Figs. 1, 2, 3 and 5 barrel supports 4, sills 6 and upright members 8 are of wood. In the wooden construction, the metal seals 18 are preferably nailed to the barrel supports 4 and sills 6. The metal strips 26 are nailed directly to the barrel supports 4. 45 The supports 4 are spaced to support the barrels at the chimes.

In Figs. 4 and 6, the barrel supports 30 are fastened upon the sills 6 and are spaced to support the barrels between the chimes. The rack structure is of wood. Sheet metal seals 32 between adjacent barrel supports in the same cell, sheet metal seals 34 between adjacent barrel supports in adjacent cells and the sheet metal seals 36 which pass under the cat-walks 16 are nailed to 55 the barrel supports 30.

In Figs. 7, 8 and 9, which illustrate the use of my invention in a metal rack structure, the upright members 38 and the barrel supports 40 are of metal, preferably of channel design. The sheet metal seals 42 between adjacent barrel supports in adjacent cells, the sheet metal seals 44 between adjacent barrel supports in the same cells, and the sheet metal seals 46 which pass under the cat-walk 48 may be conveniently fastened to the 65 upright members 38 and the barrel supports 40 by means of wires 50, the ends 52 of which are twisted to provide a tight hold. The barrel supports 40 are attached to the upright members 38 and are spaced to support the barrels at the 70 chimes.

In the rack structure shown in Figs. 10 and 11 the barrel supports 54 are spaced to support the barrels between the chimes. These barrel supports 54 are supported by the sills 56, which are supported by the upright members 58. In this

construction the sheet metal seals 60 are fastened to the sills 56 by means of wires 62.

In storage houses of this kind, it is necessary to employ one or more elevators. In order to prevent the spread of fire through the elevator shaft, there are preferably provided, at each of the floor levels having the sheet metal sealing means, the swinging doors 64 and 66 disposed within the elevator shaft 68. The swinging doors 64 and 66 may be made to automatically operate, as by means of a fusible catch 70, which, when heated to a given temperature will melt and release the doors 64 and 66, allowing these doors to drop from the vertical or open position shown in Fig. 13 to the horizontal position shown in Fig. 14 and close the opening in the elevator shaft at such floor level. It is preferable also to face these doors 64 and 66 with metal, and to provide on one of these doors a flap 72 attached thereto by spring hinges 74 which will be released when the door 66 is released and thereby provide a more effective seal at the edges of the doors.

In using my sheet metal sealing means in a rack structure made of material having a different coefficient of expansion from that of the sheet metal, it is desirable to provide for the differences in expansion and contraction of the different materials. The sheet metal seals 18, 32, 34 and 36 in the wooden rack structures illustrated in Figs. 1 to 6 are of channel form and thus provide for expansion and contraction. The sheet metal strips 26 are formed with the ridges 76 and the sheet metal strips 28 are formed with the ridges 78 to provide the heat 35 expansive means.

The application of the sheet metal sealing means to rack structure, as heretofore described, results in a highly efficient means for preventing the spread of fire from the space in the rack below the sealing means to the space in the rack above the sealing means. The amount of fire-extinguishing fluid issuing from the sprinklers used in racks, while sufficient to extinguish a fire when confined within the space between the sealing means, has been found insufficient and non-dependable to extinguish or even check a fire when it is permitted to spread throughout the rack structure. By so confining the fire to restricted space, the fire-extinguishing fluid released from the sprinklers can be depended upon to extinguish the fire. The fire-proof doors in the elevator shaft also aid in preventing the spread of fire.

The sheet metal sealing means, employed as 55 herein shown, do not diminish the storage capacity of the racks and offer no impediment to the storing and removal of the barrels from the racks.

The present invention is not limited to the 60 specific details set forth in the foregoing examples which should be construed as illustrative and not by way of limitation, and in view of the numerous modifications which may be effected therein without departing from the spirit and 65 scope of this invention, it is desired that only such limitations be imposed as are indicated in the appended claims.

I claim as my invention:

1. A storage rack having a plurality of floor 70 levels, means at one of said floor levels for sealing the space in said rack above said floor level from the space in said rack below said floor level, said means comprising sheet metal attached to the structure of said rack at said floor level and 75

- disposed to cover the voids in the rack structure at said floor level.
2. In a storage rack for barrels containing aging liquid, a plurality of floor levels, barrel supports at said floor levels, means at one of said floor levels for sealing the space in said rack above said floor level from the space in said rack below said floor level, said means comprising sheet metal attached to the barrel supports and to other parts of the structure of said rack at said floor level and disposed to cover the voids at said floor level between said barrel supports and the voids at said floor level between other parts of said rack structure.
- 15 3. In a storage rack for barrels containing aging liquid, a plurality of floor levels, barrel supports at said floor levels, means at one of said floor levels for sealing the space in said rack above said floor level from the space in said rack below said floor level, said means comprising sheet metal attached to the barrel supports and to other parts of the structure of said rack at said floor level and disposed to cover the voids at said floor level between said barrel supports, the voids at said floor level between other parts of said rack structure, and the voids at said floor level between said barrel supports and other parts of said rack structure.
- 25 4. A storage rack having a plurality of stories including stories with floor levels having means for sealing the space in said rack above each of said floor levels from the space in said rack below said floor level, said means comprising sheet metal attached to the structure of said rack at said floor levels and disposed to cover the voids in the rack structure at said floor levels.
- 30 5. A storage rack having a plurality of stories including alternate stories with floor levels having means for sealing the space in said rack above each of said floor levels from the space in said rack below said floor level, said means comprising sheet metal attached to the structure of said rack at said floor levels and disposed to cover the voids in the rack structure at said floor levels.
- 35 6. In a storage rack for barrels containing aging liquid, a plurality of stories including stories with floor levels having means for sealing the space in said rack above each of said floor levels from the space in said rack below said floor level, barrel supports at said floor levels, said sealing means comprising sheet metal attached to the

structure of said rack at said floor levels and disposed to cover the voids at said floor levels between said barrel supports, the voids at said floor levels between other parts of said rack structure, and the voids at said floor levels between said barrel supports and other parts of said rack structure.

7. A storage rack having a plurality of floor levels, means at one of said floor levels for sealing the space in said rack above said floor level from the space in said rack below said floor level, said means comprising sheet metal having heat expansive portion and attached to the structure of said rack at said floor level and disposed to cover the voids in the rack structure at said floor level.

8. A storage rack of wooden structure having a plurality of floor levels, means at one of said floor levels for sealing the space in said rack above said floor level from the space in said rack below said floor level, said means comprising sheet metal attached to the structure of said rack at said floor level and disposed to cover the voids in the rack structure at said floor level.

9. A storage rack of metal structure having a plurality of floor levels, means at one of said floor levels for sealing the space in said rack above said floor level from the space in said rack below said floor level, said means comprising sheet metal attached to the structure of said rack at said floor level and disposed to cover the voids in the rack structure at said floor level.

10. In a storage rack for barrels containing aging liquid, a plurality of floor levels, barrel supports at said floor levels, means at one of said floor levels for sealing the space in said rack above said floor level from the space in said rack below said floor level, said means comprising sheet metal attached to the barrel supports and to other parts of the structure of said rack at said floor level and disposed to cover the voids at said floor level between said barrel supports, the voids at said floor level between other parts of said rack structure, and the voids at said floor level between said barrel supports and other parts of said rack structure, a hallway having a walk at said floor level, and sheet metal sealing means attached to said walk and disposed to cover voids in the structure of said walk.

CLARENCE EUGENE TOVELL. 50
